Patented Oct. 14, 1919.

FIG. 1.

FIG. 2.

Inventor

J. E. Willert

By Edgar M. Kitchin,
his Attorney.

UNITED STATES PATENT OFFICE.

JOHN E. WILLERT, OF PASSAIC, NEW JERSEY, ASSIGNOR OF ONE-HALF TO DAVID J. O'BRIEN, OF NEW YORK, N. Y., AND ONE-EIGHTH TO WILBUR L. WRIGHT, OF FULTON, NEW YORK.

HUMIDOR.

1,318,939.

Specification of Letters Patent. Patented Oct. 14, 1919.

Application filed February 6, 1918. Serial No. 215,612.

To all whom it may concern:

Be it known that I, JOHN E. WILLERT, a citizen of the United States, residing at Passaic, in the county of Passaic and State 5 of New Jersey, have invented certain new and useful Improvements in Humidors; and I do hereby declare the following to be a full, clear, and exact description of the invention, such as will enable others skilled in 10 the art to which it appertains to make and use the same.

The present invention relates to humidors or moisteners, and has for an object to provide a compact humidor in the form of a 15 package or container particularly adapted for cigars and the like and in which the cigars may be packed, vended and subsequently maintained in large or small quantities in a moist and proper condition.

20 The invention provides a container which may be easily and economically made of card-board, or other light and economical material, suitably treated for rendering the same air and moisture-proof, in small and 25 large sizes to accommodate a small or large number of cigars, and which embodies a construction for carrying in a small space and out of contact with the cigars a moistener for properly conditioning the cigars 30 and for maintaining them in such condition for gradual consumption; the moistener being adjustable upon the top and bottom of the container for applying more or less moisture to the cigars as is found desirable; and 35 the moistening pad being easily removable as often as deemed necessary.

With these and further objects in view as will in part hereinafter become apparent and in part be stated, the invention comprises certain novel constructions, combinations and arrangements of parts as subsequently specified and claimed.

In the accompanying drawing,—

Figure 1 is a vertical section through a 45 container constructed according to the present invention.

Fig. 2 is a plan view of the detachable moistener cap employed.

Referring to the drawing by numerals, 50 10 designates a container body which may be cylindrical in form as shown and may be constructed of water and moisture-proofed card-board, although any other suitable economical material may be employed. The

55 container body 10 is closed at its lower end by a perforated bottom 11 in the form of a disk having a depending marginal flange 12 fitting snugly in the lower end of the container and engaged by the inwardly and upwardly rolled lower edge 13 of the container 60 body 10 to hold the bottom 11 in place. The flange 12 serves as a spacer for maintaining the bottom 11 above the plane of the lower edge of the container body, and the space 65 within the container body and beneath the bottom 11 forms an air chamber.

The upper end of the body 10 is closed by a removable cap 14, and fitted over the lower end of the body 10 is a moistener cap 15. The caps 14 and 15 may be constructed of 70 the same material as that of the body 10, and comprise annular bands having their outer edges rolled inwardly and returned for engaging marginal flanges 16 formed upon the disks or heads 17 of the caps. The moistener cap 15 is of suitable depth for carrying a partition disk 18 which is perforated and provided with a spacing flange 19 turned inwardly from the marginal edge of the disk 18 and adapted to seat upon the 80 head 17 of the moistener cap to space the partition 18 therefrom. The flange 19 is of a depth adapted to position the partition disk 18 inwardly of the marginal edge of the moistener cap to admit the overlapping 85 of said edge over the end of the container body 10. The space between the partition 18 and the head 17 of the moistener cap forms a chamber for the reception of a moisture-retaining element 20 in the form of 90 a pad or the like absorbent adapted to absorb a liquid for moistening the air in the container.

If desired, the evaporation of the moisture from the pad 20 may be controlled by 95 a valve 21 of substantially disk form pivoted to the partition disk 18 by an eyelet 22, or the like, arranged axially within the moistener cap and upon which the valve 21 is adapted to turn. As shown in the present 100 instance, the perforations of the partition disk 18 may be arranged in spaced groups and the valve 21 may comprise an imperforate body adapted to be adjusted to the desired extent over the perforations to close 105 the desired number of the same. The valve 21 is placed against the exposed side of the partition 18 so that the valve may be en-

gaged by the fingers for adjustment when the moistener cap 15 is removed from the body.

The partition 18 forms an air chamber in 5 the outer end of the cap 15 and a moistener chamber in the inner end of the cap, the lower edge of the body portion 10 projecting into the air chamber and holding the perforated bottom 11 in spaced relation to 10 the perforated partition 18.

In use, when the pad 20 is saturated with water, or the like, it is placed in the cap 15 beneath the partition disk 18, and the cap 15 may then be fitted over the lower end 15 of the body 10. The articles contained within the body are housed therein by the closure cap 14, and the evaporation of the moisture from the pad 20 saturates the air in the air chamber by circulation of the air through 20 the perforations in the partition 18. The air in the air chamber passes up through the perforations in the bottom 11 and the moisture from the air is absorbed by the articles. The upwardly spaced bottom 11 maintains 25 the articles out of contact with the partition 18 and the moistening pad 20. If desired, the caps 14 and 15 may be interchanged or the cap 15 placed on the upper end of the receptacle in lieu of the cap 14. 30 In this instance the moisture-laden air moves down through the container body 10 and effects the more complete and quick moistening of the articles. In this manner the articles may be maintained in the desired moist condition, and when the valve 35 21 is used the moistening pad 20 may be more or less cut off from access to the air contained in either the top or bottom of the container.

40 The device is particularly useful in packing and vending small quantities of cigars, as the latter may be packed and sealed in the container, and when the package is opened the pad 20 may be saturated with 45 water and adjusted in the desired manner for maintaining the cigars in the desired moist condition. While in the above description the device is described as having the moistening pad 20 and the perforated 50 partition 18 in one cap only, it is to be understood that these devices may be placed in both caps if so desired.

What I claim is:—

1. A humidor comprising a container body, 55 a cap for closing an end of the container body and including an imperforate head adapted to rest against the end of the container body walls, and a flange carrying said head and snugly embracing the outside of 60 the container walls but otherwise unsecured thereto, whereby to permit the cap to be entirely separated and removed from said container body, a perforated bottom on which

articles may rest arranged in and spaced above the lower end of said container body, 65 a moistener cap for closing an end of the container body and including an imperforate head, a short flange carrying said last-named imperforate head and snugly embracing the exterior of the container body walls to hold the moistener cap in place but otherwise unconnected therewith to admit of the removal of the moistener cap from either end of the container body and its interchangeability with said first-named cap, 70 a perforated partition carried by said moistener cap flange and spaced from the imperforate head carried thereby, an absorbent material held in the space between said partition and head, said partition being 80 spaced from said perforated bottom.

2. A humidor including a container body, a perforated disk forming a bottom for the body on which articles may rest, said disk being spaced inwardly from the lower end 85 of the container body and having a marginal depending flange fitting against the container body walls, the lower end of such walls being rolled over said flange to hold the disk in place, interchangeable caps for closing the upper and lower ends of the container body, each cap consisting of a head having an out-turned flange and a band adapted to slidingly fit over the outside container walls to hold the cap in place and 95 having an edge thereof rolled over on said head flange to hold the head and band together, a perforated partition placed in one cap and having a marginal out-turned flange snugly fitting with the cap band and resting 100 against the cap head to space the latter from said partition, and an absorbent material in the space between the cap head and partition.

3. A humidor including a container body, 105 a perforated bottom in the body spaced above the lower end thereof, interchangeable caps for closing the upper and lower ends of said body, a moistening pad carried by one of said caps and adapted to be placed 110 at either the lower or upper end of the container body by reason of the interchangeability of said caps, a partition in said cap inwardly of the moistening pad and having spaced groups of perforations therein, a 115 valve plate on the inner side of said partition adapted to revolve and open or close said perforations, said valve plate being accessible when the cap is removed.

In testimony whereof I affix my signature 120 in presence of two witnesses.

JOHN E. WILLERT.
